[57] **CLAIM**

The ornamental design for a vent sill rail extrusion, as shown and described.

DESCRIPTION

FIG. 1 is a fragmentary top perspective view of the vent sill rail extrusion showing my new design; FIG. 2 is a left elevational view thereof broken away to indicate indeterminate length; FIG. 3 is a right elevational view thereof broken away to indicate indeterminate length; and FIG. 4 is a front elevational view to a reduced scale in which the rear elevational view is a mirror image of the front view.

FIG. 1**FIG. 4****FIG. 2****FIG. 3**
